(57) **CLAIM**

The ornamental design for a children's toothbrush, as shown and described.

DESCRIPTION

FIG. 1 is a front elevation view of a children's toothbrush showing our new design;

FIG. 2 is a right side elevation view thereof, the left side elevation view being a mirror image of the right side elevation view seen herein in FIG. 2; and,

FIG. 3 is a back elevation view thereof.

1 Claim, 1 Drawing Sheet

FIG. 1

FIG. 2

FIG. 3
